UNITED STATES PATENT OFFICE.

EDWARD A. EVERETT, OF NEW YORK, N. Y.

MEANS FOR FOCUSING LAMPS.

1,307,855.

Specification of Letters Patent. Patented June 24, 1919.

Application filed July 1, 1918. Serial No. 242,899.

To all whom it may concern:

Be it known that I, EDWARD A. EVERETT, a citizen of the United States, and resident of 123 Liberty St., New York, in the county 5 of New York and State of New York, have invented a certain new and useful Means for Focusing Lamps, of which the following is a specification.

This invention relates to lamps in which 10 a source of light is projected through a lens and more particularly to a means for adjusting said light with relation to the lens.

Its objects are to provide a simple, inexpensive, reliable and convenient means for 15 adjusting a light with relation to a lens so that it may be accurately adjusted to the focal point of said lens. Reference should be had to the accompanying drawings forming part of this specification, in which, Figure 1, is a plan view on the line $x-y$ of Fig. 2; Fig. 2, is an elevation, partly in section, on the line $o-p$ of Fig. 1; Fig. 3, illustrates the principle of the adjustment and Fig. 4, is a detail of one of the parts.

25 One of the uses to which this invention is applied is to illuminate railway signals. These signals are lighted electrically from a low voltage battery E, and for reasons of economy in battery consumption, the amount 30 of illumination is necessarily limited. In order to obtain proper illumination through the lens it is necessary that the light be accurately focused so that the maximum effect may be obtained from it. Lamps are 35 changed from time to time and the center of the light may, in consequence, vary, hence a convenient method of adjustment is essential. This invention, in a simple manner, provides for minutely and independently adjusting the light in a horizontal and vertical plane.

In the drawings, A is the base of the lamp, preferably of insulating material; B is a supporting piece. C designates the lamp consisting of an ordinary commercial socket 24 supporting an electric bulb 17. 11 is a bolt which, by means of the wing nut 12 clamps the supporting piece B to the base through the slot opening 13. 14 is a circular opening 50 in the end of B through which the tubular stem 15 of the lamp socket 24 is loosely placed and held in position by the adjusting nuts 16. 18 is the center of illumination or filament. 19 is the terminals to which the 55 battery wires 28, 29 connect and from which the insulated flexible conductors 20 and 21

are led into the hollow lamp stem 15. These wires are placed within a groove 22 in the base A.

The container for the lamp is shown in 60 outline on the drawings. 31 is the lens, 51 is the case, 52 is a shield for the lens and 53 is a door which exposes an opening in the case extending from 54 to 55. Through this opening the lamp must be inserted and the 65 adjustment made.

When the wing nut 12 is released it is apparent that the lamp may be moved to the right or left, Fig. 1, by means of the slot 13. At the same time the lamp may be 70 moved at right angles on the bolt 11 as a pivot. The extent of these movements is limited by the size and shape of the opening 35 in the base, which, in this case is circular and is engaged by the stem 15 of the socket 75 24. It will be found that the area through which the lamp may move in a horizontal plane is represented by the contour shown at 32, Fig. 3. The vertical position of the filament is determined by the clamping nuts 16 80 which can be adjusted to raise or lower it; this adjustment may be represented by the rectangle 33, Fig. 3. In this way every possible adjustment necessary to bring the light into the focus of the lens is provided for. 85

Attention is called to the fact that these 90 adjustments are made without disturbing the electrical connections in any way. This is an important feature since the adjustment must be made while the lamp is lighted. To facilitate adjustment the adjusting nut is placed toward the opening in the case which is comparatively small. The limited swing of the lamp prevents the supporting piece B making a short circuit with either of the terminals 19. As this arrangement is largely composed of ordinary apparatus a comparatively inexpensive means of adjusting a lamp is provided that may be used for any 95 purpose.

Having thus described my invention, I 100 claim:

1. In combination, a lens, an electrically lighted lamp, a supporting piece for said lamp, an insulated base block to which said supporting piece is adjustably secured, a plurality of spaced terminals on said base block and conductors from said terminals to said lamp, means for positioning said lamp vertically and horizontally without disturbing its connection, and an opening in said base block for limiting its position horizontally. 110

2. In combination, a lens, a lamp, a heavy slotted supporting piece B for said lamp supported on one end, an insulated base to which said supporting piece is pivotally secured, an opening in said base arranged to engage with a part of said lamp, and means for positioning said lamp vertically and horizontally relative to said lens.
3. In combination, a lens, a lamp having a screw stem, an insulated base with an aperture, a slotted supporting piece clamped to said base and capable of moving horizon-

tally thereover, said screw stem clamped to said supporting piece by an adjusting nut on each side of said supporting piece, and the aperture in said base arranged to limit said horizontal motion. 15

Signed at New York in the county of New York and State of New York this 24th day of June A. D. 1918.

EDWARD A. EVERETT.
